UNITED STATES PATENT OFFICE.

CHARLES WILLIAM SCHILLING, OF PORTLAND, OREGON.

SPRING-BOARD ATTACHMENT FOR FELLING TREES.

SPECIFICATION forming part of Letters Patent No. 766,394, dated August 2, 1904.

Application filed December 10, 1903. Serial No. 184,689. (No model.)

To all whom it may concern:

Be it known that I, CHARLES WILLIAM SCHILLING, a citizen of the United States, and a resident of Portland, county of Multnomah, and State of Oregon, have invented a new and useful Spring-Board Attachment for Felling Trees, of which the following is a specification, reference being had to the accompanying drawings as constituting a part thereof.

10 My invention has for its object to obtain some effective yet inexpensive means for affixing what is known as a "spring-board" to a tree, being a sort of platform on which the lumberman stands while cutting down the tree.

15 My invention further has for its object to make the spring-board adjustable, so that the same may be readily propped up if the outer end thereof sags too much and also to allow 20 the spring-board to be arranged at any convenient angle in a horizontal plane.

I obtain my object by the device illustrated in the drawings above referred to.

In such drawings, Figure 1 is a side elevation of my device, partly in section. Fig. 2 is a front end elevation of my device with the spring-board removed. Fig. 3 is a plan or top view of my invention as shown in Fig. 1, excepting that the shaft *d* has been 30 given a quarter-turn, so as to project the ends of the blades *d'*, as done in practice.

Referring now to the letters as designating the parts described, my attachment consists of a plate *B*, the head end *b'* of which is bent at 35 an angle. Integrally made with the plate *B* is a wedge-shaped driving-head *c*, having a central portion *c'* cut out. In the opening so provided is journaled a shaft *d*, made with a series of knife-edge blades *d'*. Said knife-edge 40 blades are of the same width as the thickness of the wedge-head *c*, so that when said blades are positioned vertically, as shown in Fig. 1, their lateral edges will not protrude beyond the side faces of said wedge-head. This construction is obviously necessary to enable the 45 wedge-head *c* to be driven into the tree without injury to said blades *d'*.

The shaft *d* is journaled by its ends *d''* *d'''* in said wedge-head and the plate *B*. To hold 50 the shaft in place, the edge of the journal-

hole on the inner face *b''* of the plate *B* is slightly chamfered, and after the shaft *d* has been inserted the edge of the shoulder *d''* is slightly upset or flared out. The projecting end *d'''* of the shaft *d* is provided with a hole 55 *e*, in which to insert a bar wherewith to give said shaft a quarter-turn.

To adapt my device to withstand the blows of the sledge in driving the wedge-head *c* into the tree, the shaft end *d''* is protected by a hammer-head *f*, and the latter is held in place by the turn-bar *p*, inserted in the hole *e*.

The spring-board *a* is removably secured to the head end *b'* of the plate *B* by a plate *g*. The latter is made with holes through 65 which to receive rods *h* *h'* and with a slot in which to receive the hook-headed pin *j*. The head end *b'* of the plate *B* is made in the form of an arc, and in the periphery thereof are made a series of notches *l*, and the plate *g* 70 has a rigid downward-projecting stud-pin *m*, which construction allows the spring-board to be supported at any convenient angle in horizontal plane. To the lower end of the plate *B* is hingedly attached a rod *o*, having 75 a threaded end. The lower end of the bolt *h'* is provided with a hinged brace-bar *k*, the lower end *k'* of which is bent at an angle and constitutes a pin adapted to be inserted in a hole therefor provided in the bracket *n*. Said 80 bracket is also provided with a wedge-head *n'*, adapted to be driven into the tree, and it is further made with a thread-hole in which to receive the threaded end of the rod *o*. The means described for supporting the 85 spring-board are substantially and cheaply made and are adapted to allow the adjustment of the spring-board as required.

In the practical use of my invention the wedge-head *c* is first driven into the tree. 90 The shaft *d* is then rotated by means of the turn-bar *p* to cause the blades *d'* to cut laterally into the tree for the purpose of securing the wedge-head in place, the blades *d'* serving this purpose the same as the threads of a 95 screw. The wedge-head *n'* is next driven into the tree, and thereafter the spring-board is fastened on the hook-headed pin *j*, and to support the outer end of the spring-board the lower end of the brace-bar *k* is inserted in 100

the bracket *n*. Should the end of the spring-board sag too much, the brace-bar *k* is again disengaged and the wedge-head *n'* extracted. The bracket *n* is thereupon slightly raised by 5 turning up on the threaded end of the rod *o*, after which the wedge-head *n'* is again driven into the tree and the brace-bar *k* readjusted in position. The joint *q* facilitates the adjustment—*i. e.*, the raising or lowering of 10 the brackets *n* for the purpose described—without removing the wedge-head *c*. Were the rod *o* to be an integral rigid part of the plate *B*, it is self-evident that the extraction of the wedge-head *n'* would exert such a leverage as to at least partly extract the wedge-head *c* at the same time. When it is desired 15 to extract the wedge-head *c*, the same is readily done by first turning the shaft *d* back, so as to bring the blades *d'* again into their 20 vertical position.

Having fully described my invention, what I claim, and desire to secure by Letters Patent, is—

1. In a spring-board attachment, the combination of a supporting-frame, a wedge-head on said supporting-frame, for fastening the same to a tree, and means for securing said wedge-head in place, after having been driven into the tree, consisting of a rotatable shaft, 25 longitudinally journaled in an opening therefor provided in said wedge-head, and integral blades on said shaft, adapted to be entirely contained within the wedge-head, and also to be laterally projected by rotating said shaft, 30 substantially as described.

2. In a spring-board attachment, the combination of a supporting-frame, a wedge-head on said supporting-frame for fastening the same to a tree; means for securing said wedge-head in place, after having been driven into the tree, consisting of a rotatable shaft, longitudinally journaled in an opening therefor provided in said wedge-head, and integral blades on said shaft adapted to be entirely contained 40 within the wedge-head, and also to be laterally projected by rotating said shaft; a rod hingedly attached to the lower end of said supporting-frame; a bracket adjustably secured on the lower end of said rod; a wedge-head on said bracket, for also fastening the same to the tree; means for removably supporting the inner end of the spring-board, on said supporting-frame; and a support, resting 45 on said bracket, supporting the outer end of said spring-board, substantially as described.

3. In a spring-board attachment, the combination comprising a supporting-plate *B*, made with a segment-head *b'*; means for affixing said supporting-plate to a tree; a hinge-pin *j* on the 50 segment-head *b'*; a rod hingedly attached to the lower end of said plate *B*; a bracket adjustably secured on the lower end of said rod; means for affixing said bracket to a tree; a spring-board, a plate *g*, attached to the inner end thereof, and provided with a slot adapted

to be inserted on said hinge-pin *j*; a hinged brace-bar *k*, the lower end of which is supported on said bracket, and means for securing the plate *g*, and the spring-board, in convenient radial position, on the segment-head 70 *b'*, substantially as described.

4. A spring-board attachment comprising a supporting-plate *B*; made with a segment-head *b'*; a hinge-pin *j*, on said segment-head, a wedge-head on said plate *B*, for fastening the 75 same to a tree; means for securing said wedge-head in place, after having been driven into the tree, consisting of a rotatable shaft *d*, longitudinally journaled in an opening therefor provided in said wedge-head, and integral 80 blades on said shaft, adapted to be entirely contained within the wedge-head, and also to be laterally projected by rotating said shaft; a rod hingedly attached to the lower end of said plate *B*; a bracket adjustably secured on 85 the lower end of said rod; means for affixing said bracket to a tree; a spring-board, a plate *g*, attached to the inner end thereof, and provided with a slot adapted to be inserted on said hinge-pin *j*; a hinged brace-bar *k*, the 90 lower end of which is supported on said bracket, and means for securing the plate *g*, and the spring-board in convenient radial position on the segment-head *b'*; substantially 95 as described.

5. A spring-board attachment comprising a supporting-plate *B*, made with a segment-head *b'*, having peripheral notches; a hinge-pin *j*, on said segment-head; a wedge-head on said plate *B*, for fastening the same to a tree; means for securing said wedge-head in place, after having been driven into the tree, consisting of a rotatable shaft *d*, longitudinally journaled in an opening therefor provided in said wedge-head, and integral blades on 100 said shaft, adapted to be entirely contained within the wedge-head, and also to be laterally projected by rotating said shaft; a rod hingedly attached to the lower end of said plate *B*; a bracket adjustably secured on the lower end of said rod; means for affixing said bracket to a tree; a spring-board, a plate *g*, attached to the inner end thereof, and provided with a slot adapted to be inserted on 105 said hinge-pin *j*; a hinged brace-bar *k*, the lower end of which is supported on said bracket; and a pin *m*, on the under side of the plate *g*, adapted to be inserted in the peripheral notches *e*, for locking said plate *g*, and the spring-board, in convenient radial position 110 on the segment-head *b'*, substantially as described.

In testimony whereof I have hereunto affixed my signature in the presence of two witnesses.

CHARLES WILLIAM SCHILLING.
